LIFE PRESERVE

Filed June 16, 1927

ATTORNEY

UNITED STATES PATENT OFFICE.

JAMES MURPHY, OF SEATTLE, WASHINGTON.

LIFE PRESERVER.

Application filed June 18, 1927. Serial No. 199,182.

This invention relates to improvements in life preservers, more particularly of the sleeveless garment type, and aims primarily to provide a life preserver the buoyancy of which may be rapidly and readily adjusted and selectively regulated to support any weight of wearer; which is especially designed and particularly adaptable to serve and function as life saving equipment on ships; which may be advantageously and effectively employed by a child or adult while learning to swim; which may be quickly put on and similarly removed; which is not bulky or cumbersome when worn; which snugly fits and conforms to the shape of the body; which is flexible and pliable in use allowing the wearer complete freedom of movement; and which may be folded or rolled into a compact bundle when not in use for storage in any readily accessible space where it may be available for emergency purposes.

Contemplated by the present invention is a life preserver embodying a sleeveless garment; means for detachably securing the same upon the wearer; a plurality of vertically disposed elongated flexible units or strips secured to the back and front of said garment in spaced parallel relation having a series of transversely disposed compartments or pockets formed in uniform spaced parallel relation therein; individual water-tight buoyant casings or air chambers sewn into said compartments or receptacles movably inserted within such pockets; and means to retain said casings within said pockets; all of which are important features and objects of the invention and are to be correlated in the broad aim of enhancing the efficiency of the apparatus for general use.

The above, and additional objects which will hereinafter be more specifically treated are attained by such means as are shown in the accompanying drawings, described in the following specification and then more clearly pointed out in the claims, which are appended hereto, and form part of this application.

With reference to the drawings, in which there is illustrated several embodiments of the invention, and throughout the several views of which like characters of reference designate similar parts:

Figure 1 is a front elevation of a life pre-

server comprehended by the present invention, as it would appear when in use.

Fig. 2 is a rear elevation of the same.

Fig. 3 is a front elevation of a bathing suit having the flexible buoyant units fabricated in accordance with the invention attached thereto.

Fig. 4 is a rear elevation of the same.

Fig. 5 is a plan view of one of the buoyant flexible units removed from the life preserver, certain parts thereof being broken away for clarity of illustration.

Fig. 6 is a fragmentary longitudinal section taken through 6-6 of Fig. 5, and

Fig. 7 is a transverse section taken through 7-7 of Fig. 5.

Beginning the more detailed description of the invention by reference to the drawings, the numeral 8 designates a sleeveless garment, formed of any suitable fabric, such as canvas, water-proofed material, or the like, to the front and rear portions of which are secured in spaced parallel relation vertically disposed elongated flexible buoyant units 9 preferably fabricated from the same material, as the correlated garment thereof, each of which comprises a straight back strip 10 and a front strip 11 stitched or otherwise suitably secured to said back strip and fashioned to provide a series of enclosed compartments 12 or a series of pockets 13 open at one end thereof and closed upon occasion by snap flaps 14, wherein water-tight buoyant casings or air chambers 15 are disposed, which latter are preferably constructed from a relatively light metal, such as aluminum, in the form of cylinders exteriorly coated with a shellac, asphaltum or pitch lacquer to prevent interior sweating. In practice, each of the cylindrical water-tight buoyant casings 15 is preferably provided with concavo-convex ends 16 and 17, respectively, the end 16 being formed integrally with the casing, while the end 17 is soldered or brazed thereto, as more clearly shown in Fig. 7.

The buoyant casings 15 are permanently sewn into the compartments 12, as shown more clearly in Fig. 5, while such casings are removably inserted within the pockets 13 for the purpose of varying the buoyancy of the unit or life preserver, said casings being positively retained within the pockets 13 against accidental dislodgement or displacement by the snap flaps 14. It will be

apparent and obvious from the foregoing and by referring to the accompanying drawings that the provision of the pockets 13 permit of the rapid and ready increase or 5 decrease of the buoyancy of the correlated unit thereof, to thus render the latter adaptable or capable of supporting any selected weight of wearer. It is to be understood that the flexible buoyant units 9 may be 10 fabricated with compartments 12 exclusively, with pockets 13 exclusively, or with some or both as desired and found convenient. In this connection I also desire to state, that while I have herein shown and 15 described the individual buoyant casings 15 as of circular cross-section, it is to be understood that such casings may be square, rectangular, elliptical or semi-circular in cross-section, as desired, and may be of any cross 20 sectional area or length to provide the required buoyancy.

Actual experience has demonstrated that while the volume or capacity of the casings or air chambers 15 may vary between two 25 to six cubic inches, the best results when flexibility and clumsiness of the correlated buoyant unit was considered have been obtained from the casings or chambers 30 having a volume or capacity of approximately three cubic inches, say a casing one inch and one quarter in diameter and three inches long. It has also been found, after extensive tests and exhaustive experiments, that a series of casings 15 having a combined 35 or aggregate volume of one hundred cubic inches is ample and sufficient to buoy up or support an adult weighing approximately one hundred and sixty pounds.

The sleeveless garment 7 may be open in 40 the front or at the side, as desired, and is provided with tapes 18, which are tied together in an obvious manner to secure the garment in operative position upon the wearer. A belt 19 passing through loops 45 20 formed upon the lower end or edge of the garment 7 serves and functions thereto to positively retain such lower end in proper position or place, at a point slightly above the hips of the wearer, and prevents creeping 50 or upward movement of the garment while in use, as will be manifest and apparent.

In Figs. 3 and 4 the numeral 21 designates a swimming suit, of well-known form, to 55 which are secured the flexible buoyant units 9 of the invention, for supporting beginners or pupils while learning to swim giving the same confidence in the water and minimizing the fear of sinking, so that such beginners 60 may devote their entire and undivided attention to learning the various swimming strokes and are thereby materially aided in more rapidly and effectively becoming accomplished swimmers.

By fabricating the flexible buoyant units 65 9 in the manner herein set forth, such units may be securely attached to or incorporated in the garment 7 or the bathing suit 21, while the same are being manufactured, or such units may be sold separately or individually for attachment by the purchaser to any garment or suit. Further, by providing cylindrical casings 15 of suitable size and transversely disposing same in uniform spaced parallel relation within their correlated units 70 9 and subsequently attaching such units to the selected garment or suit in vertically disposed spaced parallel relation upon the front and back thereof, as herein shown, it will be obvious, that an extremely flexible apparatus 75 snugly fitting and conforming to the shape of the wearer's body is provided, that is not cumbersome, and that will readily permit of free bending or flexing of the body, where heretofore the life preservers 80 in general use were rigid, bulky and unwieldy, and when in use positively prevented free body movements of the wearer.

Manifestly, therefore, the apparatus of the 85 invention is extremely simple in construction, inexpensive to manufacture, convenient, durable, efficient and reliable in use, and in the event of fracture or rupture of any of the buoyant casings or air chambers 15 thereof, the remaining undamaged casings will be 90 sufficient to furnish the necessary buoyancy to properly support the wearer.

While I have herein shown and described the invention with sufficient detail to enable those skilled in the art to understand the 100 mode of construction and the principles involved, it is to be understood that there is no intentional limitation herein to the specific form and precise details of construction 105 herein disclosed, except as expressly defined by the appended claims, and that various modification of said construction may be resorted to without departing from the invention, or the benefits derivable therefrom. I also desire to have it understood that certain 110 features of the invention herein disclosed may be employed in other combinations than those shown and described.

Having thus fully described my invention, what I claim as new and desire to secure by 115 Letters Patent is:—

1. A flexible life preserver comprising a garment, means for detachably securing the same upon the wearer, a series of vertically disposed flexible strips secured to the front 120 and rear of said garment in spaced parallel relation thereon, said strips having a series of transversely disposed compartments formed therein and a series of similarly disposed pockets formed therein, individual 125 water-tight cylindrical air containers permanently sewn within said compartments and similar containers removably seated

within said pockets, and means to retain said last named containers within their correlated pockets.

2. In combination with a garment, of a flexible buoyant unit comprising a strip of flexible material having a series of transversely disposed compartments formed therein and a series of similarly disposed pockets formed therein, individual water-tight cylindrical air containers permanently sewn within said compartments and similar containers removably seated within said pockets, and means to retain said last named containers within their correlated pockets.
- 10 3. A flexible life preserver comprising a garment, a vertically disposed relatively

long flexible strip centrally secured to said garment having a series of transversely disposed compartments formed therein, individual water-tight cylindrical containers 20 permanently sewn within said compartments, vertically disposed relatively short flexible strips secured to said garment upon each side of said first-named strip in spaced parallel relation thereto having a series of transversely disposed pockets formed therein, individual water-tight cylindrical air containers removably seated within said pockets, and means to retain said last named containers within their correlated pockets. 25

In testimony whereof I affix my signature.
JAMES MURPHY.
